(57) **CLAIM**

The ornamental design for a medical imaging apparatus, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of an embodiment of a medical imaging apparatus showing our new design;

FIG. 2 is a back elevational view thereof;

FIG. 3 is a top plan view thereof;

FIG. 4 is a bottom plan view thereof;

FIG. 5 is a right side elevational view thereof;

FIG. 6 is a left side elevational view thereof; and

FIG. 7 is a perspective view taken generally from the front, left-hand side thereof.

FIG. 8 is a front view of another embodiment of a medical imaging apparatus showing our new design;

FIG. 9 is a back elevational view thereof;

FIG. 10 is a top plan view thereof;

FIG. 11 is a bottom plan view thereof;

FIG. 12 is a right side elevational view thereof;

FIG. 13 is a left side elevational view thereof; and,

FIG. 14 is a perspective view taken generally from the front, left-hand side thereof.
